UNITED STATES PATENT OFFICE.

TRAVICE R. HOUSTON, OF LOUISVILLE, KENTUCKY.

FIRE-GRAVE.

SPECIFICATION forming part of Letters Patent No. 241,364, dated May 10, 1881.

Application filed February 19, 1881. (No model.)

To all whom it may concern:

Be it known that I, TRAVICE R. HOUSTON, a citizen of the United States, resident at Louisville, in the county of Jefferson and State 5 of Kentucky, have invented certain new and useful Improvements in Fire-Grates; and I do hereby declare the following to be a full, clear, and exact description of the invention, such as will enable others skilled in the art to which 10 it appertains to make and use the same, reference being had to the accompanying drawings, and to letters or figures of reference marked thereon, which form a part of this specification, and in which—

15 Figure 1 is a representation of a front view. Fig. 2 is a vertical section. Fig. 3 is a horizontal section, and Fig. 4 is a perspective detail. Fig. 5 represents a portion of the device in section, showing the construction of the lip. 20 This invention relates to improvements in grates.

The invention consists in the construction hereinafter described.

In the annexed drawings, A is a chimney having the fire-place B. In the edges b of this fire-place are secured, one above the other, the pins C C', and opposite each other, on the inside, are the holes D D'. 25

E is a front of somewhat the usual shape, 30 having at the top the hooks e.

F is a back for the grate, consisting of the two bars f f', connected by the cross-bars z, curved at y, at bar f', the bar f having the extended ends y' y'', one a little longer than the 35 other, and bar f' having at the middle an extension, f''. This back is put in place by inserting its ends y' y'' into the holes D D', the bars z curving backward, and bar f' falling in under a lip, n, in the back of the fire-place, the 40 extension f'' covering hole l' at the back of fire-place. The lip n, as shown in Figs. 1 and 5, is made at the back, across the same, so as to come at a point where the bar f' will fall under it. The front E is put in place by hanging 45 the hooks e over the pins C C, the side bars, p p, of the front resting against the pins C' C'.

The bar f of the back F has at its middle the hook f'', composed of two fingers, f', and on these the lower bar of the front E catches when in place.

F' F'' are flues in the sides of the chimney, running from the openings l l in the bottom of the chimney, leading into the room to the apertures k k, which open into the fire-place at the sides back of the grate.

K is a valve closing the opening l.

At the back of the fire-place, below the grate, is an opening, L, and just at rear of the grate, where extension f'' comes, another opening, l', these two being connected through the chimney by the flue M. This furnishes air to the fuel at the back, the opening l' extending down, so as to be partly behind the back F and partly above, the extension f'' in this latter instance covering the opening, and while permitting 65 draft prevents fuel from falling into flue M, and yet it can be readily swung aside with the back to clean out the flue. These openings in the sides and back supply the fire with air all around, whereby combustion is facilitated and 70 the consumption of the fuel is better insured.

What I claim is—

1. The front E, having hooks e e, in combination with the chimney having pins C C', and back F, having hook f'', substantially as described.

2. The combination of a fire-place provided with side flues and a flue at the back opening below and at the rear of the grate, with a grate composed of a back pivoted in the sides of the 80 fire-place, and having an extension which covers the upper opening of the back flue, and a front which is hooked upon supports in the wall of the fire-place, and the lower bar of which engages a hook on the back, all as set forth.

In testimony whereof I affix my signature in presence of two witnesses.

T. R. HOUSTON.
